UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed November 3, 1925. Serial No. 66,495.

This invention relates to compressors, but more particularly to a simple and cheap unloading device for the compressor, particularly adapted for double acting cylinders 5 for unloading the compressor step by step.

The object of the invention is to permit successive unloading in steps by means of one clearance chamber which is also utilized as a by-pass between the ends of the cylinder for complete unloading.

Further objects of the invention will hereinafter appear and the invention is shown in one of its preferred forms in the accompanying drawings, in which—

15 Figure 1 is a diagrammatic side elevation partly in section and partly broken away of a double acting compressor cylinder and automatic regulator, and

20 Figure 2 is a transverse sectional elevation on the line 2—2 of Figure 1 looking in the direction of the arrows.

Referring to the drawings, the cylinder A is provided with a double acting piston B driven from any suitable motor or engine and the cylinder is provided with suitable inlet and discharge valves C and D indicated diagrammatically as of the plate type. Air enters at the inlet E and is discharged through the discharge connection F 30 to the receiver G.

A by-pass connection H from one end of the cylinder to the other is of sufficient capacity to form a clearance chamber and is controlled by the clearance valves J and K 35 controlling the valve openings L and O respectively and operating in the valve cylinders P and Q connected by the pipes R and S to the automatic regulator T of any suitable type controlled by receiver pressure 40 led to the regulator by the pipes U, V and W. The construction and arrangement of the regulator is such that upon a predetermined increase of receiver pressure, first, one clearance valve J is opened to partially

45 unload the compressor due to the capacity of the clearance chamber H, and upon a further increase of receiver pressure the clearance valve K is automatically opened, thus opening the clearance chamber H to both ends of the cylinder and forming a by-pass for complete unloading. Although I 50 have only shown two steps of unloading, it is to be understood that a greater number of steps may be provided, if desired, by 55 means of intermediate clearance chambers.

The regulator T comprises a casing X having a diaphragm Y, and the receiver pipe V supplies pressure to the diaphragm chamber a. A pin b in the guide c, which bears on the diaphragm, supports a weighted lever 60 e pivoted at the point f to a projection g on the regulator casing X. An auxiliary valve or pilot valve h having the heads j and k controls ports and passages leading to the main operating valves o and p which 65 reciprocate in the valve chambers q and r, and these valve chambers are constantly open to receiver pressure between the heads s and t of the main valves by means of the connection u from the diaphragm chamber a 70 opening into the chambers or spaces q and r by means of the ports v and w respectively. The valves o and p are provided with shoes x and y controlling the ports 3 and 4 in the regulator.

75 The receiver pipe W constantly supplies pressure at the point 5 to the regulator between the heads j and k of the pilot valve h and in full load position of the regulator the pilot valve is at the lowermost point of 80 its travel, the drawing showing the pilot valve in Figure 1 raised through one step due to an increase of receiver pressure to effect its movement so that the clearance valve J is open, but under normal conditions both clearance valves will be closed and both passages 6 and 7 in the regulator valve casing X will be opened to receiver pressure from the pipe W so that both main valves o and p will be in their right 85 end positions. In such case the heads s of the valves o and p will be opened to atmosphere through the passages 8 and 9 and the open end 10 of the pilot valve casing. Receiver pressure from the valve chambers q and r will then pass through the ports 3 and the pipes R and S respectively to the clearance valve cylinders P and Q to hold the clearance valves closed.

90 Upon an increase of receiver pressure to 100 a predetermined degree, for the first step of unloading the lever e will be raised, raising the pilot valve h to the position indicated in Figure 1. In such case the main valve p will be moved to the left due to the release 105 of pressure at the left hand end through the passage 7 which is then opened to atmosphere through the atmospheric port 12 in the pilot valve casing, receiver pressure being admitted through the passage 9 to 110

the right end head *s* of the valve *p*. The ports 3 and 4 controlled by the shoe *y* will be placed in communication and the pipe *R* leading to the clearance valve *J* will be opened to atmosphere through the atmospheric port 13, thus releasing the pressure behind said valve and permitting the valve to open due to the pressure in the cylinder, thus partially unloading the compressor to any desired degree depending upon the capacity of the clearance chamber *H*. A further increase of receiver pressure to a predetermined degree will raise the lever *e* still further and the main valve *o* will be thrown to the left and the pipe *S* will be placed in communication with atmosphere through the atmospheric port 14 relieving the pressure behind the clearance valve *K* and causing the clearance chamber *H* to become an open by-pass connection between the ends of the cylinder. Obviously this regulator may be operated by hand instead of automatically.

I claim:

25 1. In a compressor unloader, the combination of a double acting cylinder and piston, inlet and discharge valves for the cylinder, a by-pass connection from one end of the cylinder to the other forming a clearance chamber, and clearance valves for each end of the cylinder controlling said clearance chambers, whereby the compressor may be unloaded in successive steps.

30 2. In a compressor unloader, the com-

bination of a double acting cylinder and 35 piston, inlet and discharge valves for the cylinder, a by-pass connection from one end of the cylinder to the other forming a clearance chamber, and automatic clearance valves for each end of the cylinder responsive 40 to receiver pressure and controlling said clearance chamber, whereby the opening of one valve partially unloads the compressor due to the added clearance chamber, and the opening of both valves completely unloads the compressor due to the open by-pass connection between the ends of the cylinder.

3. In a compressor unloader, the combination of a double acting cylinder and 50 piston, inlet and discharge valves for the cylinder, a by-pass connection from one end of the cylinder to the other forming a clearance chamber, automatic clearance valves for each end of the cylinder responsive to 55 receiver pressure and controlling said clearance chamber, whereby the opening of one valve partially unloads the compressor due to the added clearance chamber, and the opening of both valves completely unloads 60 the compressor due to the open by-pass connection between the ends of the cylinder, and an automatic regulator for controlling said clearance valves.

In testimony whereof I have signed this 65 specification.

CHESTER W. METZGAR.
